UNITED STATES PATENT OFFICE.

ANTON VAN VEEN, OF NEW BRITAIN, CONNECTICUT, ASSIGNOR TO THE FULLER BRUSH COMPANY, OF HARTFORD, CONNECTICUT, A CORPORATION OF CONNECTICUT.

WIRE-BENDING MACHINE.

Application filed November 22, 1922. Serial No. 602,503.

This invention relates to the class of machines more especially adapted for bending wire structures in which bristles have been attached to a wire core as by a twisting operation, and an object of the invention, among others, is to provide a machine that shall be particularly efficient both as to the rapidity of its operation and the character of work performed.

10 One form of machine embodying the invention and in the construction and use of which the objects herein set out, as well as others, may be attained, is illustrated in the accompanying drawings, in which—

15 Figure 1 is a view in side elevation of the improved machine with the driving pulley removed.

Fig. 2 is a top view of the same with parts broken away on a plane denoted by the dotted line 2—2 of Fig. 1, the mechanism being shown in position at the termination of a bending operation, and with the delivery chute removed, but shown in dotted lines.

20 Fig. 3 is a view similar to Fig. 2 but with the delivery chute in place and the feed device removed, and the parts being shown in their normal positions of rest.

Fig. 4 is a view of a portion of the structure as shown in Fig. 3, but with the bending mechanism in an intermediate position.

25 Fig. 5 is a view in horizontal section on a plane denoted by the dotted lines 5—5 of Figs. 1 and 6, the bending slide being shown in a rearward position.

Fig. 6 is a view in vertical section on a plane denoted by the dotted line 6—6 of Fig. 3, but with the bending arms in their forward or bending positions.

30 Fig. 7 is a detail view, scale enlarged, illustrating the grippers and on a plane denoted by the dotted line 7—7 of Fig. 2.

Fig. 8 is a detail view, also on enlarged scale, of a portion of the machine on a plane denoted by the dotted line 8—8 of Fig. 2.

35 Fig. 9 (Sheet 1) is a detail view illustrating the operation of the feed device.

In the accompanying drawings the numeral 10 denotes the base of the machine having a base block 11 secured thereto in any suitable manner, this block being preferably separately formed and attached as by means of bolts. This base block is made hollow

with sides 12—13 located opposite each other, and a table 14 forms the top of a chamber 15 within the base block, there being openings 16—17 into this chamber through opposite sides of the base block.

Straps 18—19 are secured to opposite sides of the base block at or near the front and back edges thereof, as shown in Figs. 1 and 2 of the drawings, said straps being removed in Figures 3 to 6, and these straps having upwardly projecting arms 20—21 forming a feed chute 22 between them for the reception of the projecting ends of brush structures 23, which structures comprise bodies of bristles secured between twisted strands of wire in a manner that will be readily understood. These brush structures are preferably manually placed in the feed chute, but any other means for supplying the chute with said structures may be provided.

A driving shaft 24 is mounted in a bearing block 25 secured to and rising from the base and is provided with any suitable driving means as a pulley 26, by means of which the machine is driven. A cam 27 and a bending crank disk 28 are secured to the driving shaft, said disk having a bending rod 29 adjustably secured thereto at one end, said rod being attached to a bending slide 30 at its opposite end. Said slide is mounted in slideways formed by a guide block 31 and a guide plate 32, said block being secured to the inner surface of the side 12 and said plate being secured to said block, as clearly shown in Figs. 5 and 6 of the drawings. A bending rack 33 is removably secured to the slide 30 with its teeth in mesh with the teeth of a bending pinion 34 in gear with another bending pinion 35. These pinions are secured to bending shafts 36—37 rotatably mounted preferably in bearing sleeves in the table 14, as shown in Fig. 6 of the drawings, the upper ends of said shafts having bending arms 38—39 secured thereto and projecting laterally therefrom.

Bending posts 40—41 are secured to and rise from said arms, as shown in Fig. 7 of the drawings, these posts being hollow to receive clamp plungers 42 located one in each post, each of said plungers having a shoulder to receive the thrust of a spring 43 bearing with one end against said shoul-

der and with its opposite end against the end wall of the chamber within the hollow post. These springs thrust the clamp plungers downwardly toward balls 44 against which the plungers seat and upon which they ride, said balls rolling over the upper surface of the table 14 and also of releasing plates 45 secured to the upper surface of the table. The upper end of each plunger is provided with a clamp 46 secured to the plunger as by means of intermeshing screw threads, and held in place as by a clamp nut, as shown in Fig. 7 of the drawings. As these clamps hold the ends of the wires of the brush structures to be bent, the downward movement of the plungers will be limited by such wires. Therefore, in order to keep the balls 44 in contact with the upper surface of the table 14 when the balls pass from the plates 45, springs 47 are located in chambers projecting inwardly from the recesses located in the bottom of each of the plungers, as shown in Fig. 7 of the drawings, within which recesses said balls 44 are located and roll.

Plunger retaining plates 48 are pivotally mounted on the table 14, the pivots for said plates having returning springs 49 (see Fig. 8 of the drawings) for returning the plates to their normal positions. The ends of these plates are beveled on their under surfaces as at 50 to correspond with the beveled upper surfaces 74 of the plates 45, the upper surfaces of the plates 45 and 48 being in the same plane. Plunger easing cams 51 are formed on the plates 48 for the purpose of easing the movement of the plungers from the upper surfaces of the plates 48 to that of the table 14 in the return movement of the plungers from their bending positions. Plunger opening plates 52 are secured to the upper surface of the table 14, the ends of these plates being beveled as shown in Figs. 3 and 4, the balls 44 riding up these beveled surfaces on the return of the plungers to their normal positions, forcing them upwardly and thereby opening the clamps 46 to receive the ends of the wires.

In the operation of the mechanism thus far described the plunger arms 38-39 being in the positions illustrated in Fig. 3, the ends of the brush structure 23 will be in the positions shown by dotted lines in Fig. 3. Said bending arms being now moved by the operation of the bending slide 30 in a direction away from the driving shaft 24, the ends of the wires will be received in the spaces between the clamps 46 and the ends of the posts 40-41. As the balls pass down the beveled surfaces at the ends of the plates 52 the plungers will move downwardly under the influence of the springs 43 and the ends of the wires will be securely clamped. As the arms 38-39 continue their bending movements they will contact with each of

the plates 48, swinging them out of the path of movement of the plungers and against the tension of the springs 49. In this movement the brush structure is held at its lengthwise center against a center bending post 53, to be hereinafter described, the bending of the brush structure taking place around such post. As the plungers approach each other the balls 44 travel up the beveled surfaces 74 on the plates 45 and the plungers are thereby raised to release the clamps 46 from the wires, and the bent structure is free to be removed by the extracting mechanism now to be described.

This extracting mechanism comprises an extractor 54 pivotally mounted on an extracting arm 55 that swings upon a pivot 56 on a support 57 secured to the side of the block 11. An extracting rod 58 extends from the arm 55 to a strap rotatably mounted on the post 40 to which it is secured, and thereby the reciprocating movement of said post is made use of to reciprocate the extractor to engage the brush structures and to remove them after they have been bent.

In the bending operation an end bending post 59 is made use of for bending the ends of the wires outwardly away from each other, and as illustrated in Fig. 2 of the drawings, this end bending post rising from the table 14 to receive the ends of the wires as they approach each other in the bending operation, and the posts 40-41 force the wires together against the resistance of the post 59 and thus bend said wires outwardly, as illustrated in Fig. 2 of the drawings.

In the bending movement of the arms 38-39, as the balls 44 pass up the beveled surfaces 74 on to the flat surfaces of the releasing plates 45, said balls are disengaged from the plunger retaining plates 48 and the latter are returned, by the springs 49, to the positions shown in Fig. 3, so that said balls, in the return movement of the bending arms, pass from the flat surfaces of the plates 45, without changing level, on to the flat surfaces of the plunger retaining plates 48, the plungers consequently being retained in their raised positions to keep the clamps 46 open during a portion of the return movement of said bending arms and long enough to permit the free disengagement of the projecting wires of the brush structures from the clamps by the extractor 54. Time is therefore saved and the speed of the machine thereby increased by providing for return movement of the bending arms during the extracting operation.

The center bending post 53 is movably mounted as by securing it to a slide 60 that has a movement in a slideway formed between guides 61, said guides being held between and secured to plates 62-63, the plates 62 forming a surface upon which the brush structures rest just prior to the bend-

ing operation, and while being bent. The slide 60 is reciprocated as by means of a slide operating rod 64 secured to a bell crank lever 65 pivotally supported between angle pieces 66 secured to and rising from the base 10. One end of the lever is secured to the rod 64 and the opposite end has a roller in contact with the cam 27 hereinbefore referred to, said roller being held in contact 10 with the cam by a spring 76 attached at one end to the lever 65 and at the other end to a spring support 77. This cam is shaped and timed to present the post 53 in the position shown in Fig. 3 when a brush is ready to 15 drop to bending position, and to move the slide 60 to position the post in the location shown in Fig. 2, the bending operation and the movement of said post to said location, in the mechanism as herein shown, taking place 20 simultaneously, the post, however, reaching the position shown in Fig. 2 before the bending operation terminates.

The feed mechanism comprises a detent supporting bar 67 pivotally attached to each 25 of the arms 20, said bars each having a detent 68 rigidly secured thereto and a beveled end to engage the projecting wire ends of the brush structures 23, these detents supporting the brush structures one upon another 30 before they are presented to the lowermost or bending position. These detents in their reciprocating movements pass between the ends of the wire core of the brush structure at the bottom of the pile and that next to 35 the bottom structure, as illustrated in Figs. 1 and 9 of the drawings. These detents are of considerable width and the ends are beveled in order that the pile of structures shall be raised in each reciprocating movement of 40 the detents. This lifts the pile from the lowermost structure, enabling the latter to be relieved of pressure during the operation of removing it after it has been bent, and, further, this raising of the pile tends to keep 45 each of the structures free and from being cramped or wedged.

An operating finger 69 is adjustably secured to a bar extending between and attached in any suitable manner to the bars 67 50 and in position to be encountered by the center bending post 53 in the movement of the latter. The detents are forced into a normal position of rest, as by means of springs 70, each secured at one end to an arm 71 rigidly 55 attached to a bar 67, the opposite ends of the springs being attached to a fixed part of the machine.

In the operation of this feed device, the extracting and feed mechanism being in the 60 position illustrated in Fig. 1 with a bending operation just completed the hooked end of the extractor 54 (see dotted lines in Figure 1) is in position for engagement with the brush structure to remove it, said extractor engag- 65 ing behind the bristles, with respect to the

extracting movement and within the bow, sufficiently for this purpose. This position of the extractor is caused by a spring located on a headed pin 72 projecting upwardly from a plate 73 attached to the arm 55. The 70 spring thrusts with one end against the head of the pin and with its opposite end against the extractor, pressing the latter downward into engagement with the brush structure for 75 extracting purposes.

As the bending arm 38 moves from its bending position into position to receive a brush structure, it operates the rod 58 and the extractor arm 55 to cause the extractor to withdraw the bent structure, that, just as soon as it passes from the plate 62, travels down the inclined delivery chute 75. In this movement of said feed arms for the purpose of receiving another brush structure, the 80 posts 40-41 pass under the pile of brush structures in the feed chute, the detent 68 not releasing such structures until after said posts have passed underneath the pile. Said arms are now moved to effect a bending operation, the extractor is moved to extracting 85 position, and in such movement it thrusts against the brush structure resting on the detent and lifts the pile to a slight degree, thus releasing any structures that may have become wedged in the chute.

In accordance with the provisions of the patent statutes I have described the principles of operation of my invention, together with the device which I now consider to represent the best embodiment thereof; but I 90 desire to have it understood that the device shown is only illustrative and that the invention may be carried out by other means.

I claim—

1. A bending machine comprising bending members to engage the ends of an article to move them toward each other and effect a complete bending of said article, said members being disengaged from the center of the article, a positioning post movably mounted to receive and support said article intermediate its ends and around which the article is bent, said post being mounted to move in a plane in which the article is bent, and means for moving the post simultaneously with the bending movement of said article.

2. A bending machine comprising bending members bodily movably mounted to engage the ends of an article to move them toward each other, and effect a complete bending of said article, said members being disengaged from the center of the article, a positioning post movably mounted for reciprocating movement, and means for moving the post in one direction simultaneously with the movement of the ends of said article in an opposite direction to bend the article around said moving post.

3. A bending machine comprising bending

- members movably mounted to engage the ends of an article to move them toward each other; said members being disengaged from the center of the article, a post mounted for reciprocating movement to receive an article intermediate its ends and around which the article is bent, and means for moving the post and the bending members concurrently in opposite directions.
10. 4. A bending machine comprising bending members movably mounted to engage the ends of an article to move them toward each other; said members being disengaged from the center of the article, a plate upon which said articles rest during the bending operation, said plate having a slot, a slide movably mounted underneath said plate, and a post projecting upwardly from said slide through said slot in position to receive intermediate their ends the articles to be bent.
15. 5. A bending machine comprising a bending member movable in a curved path, a post mounted on said member to engage an end of an article to move it along said curved path for bending purposes, a clamp on the end of the post to receive said end, and means for resisting movement of said article intermediate its ends.
20. 6. A bending machine comprising a bending member movable in a curved path, a post mounted on said member, a clamp movably mounted on the end of said post to receive an end of an article to be bent along said curved path, means for operating said clamp, and means for resisting movement of said article intermediate its ends.
25. 7. A bending machine comprising a bending member movable in a curved path, a post mounted on said member, a plunger located in said post and projecting beyond the end thereof, a clamp secured to the projecting end of said plunger to receive the end of an article to be bent and move it along said curved path, means for operating said clamp and plunger, and means to resist movement of said article intermediate its ends.
30. 8. A bending machine comprising a bending member movably mounted, a post mounted on said member, a plunger located in said post and projecting beyond the end thereof, a clamp secured to the projecting end of said plunger to receive the end of an article to be bent, an anti-friction device engaging the end of said plunger and upon which it rides, means to engage said anti-friction member to operate said clamp, and means to resist movement of said article intermediate its ends.
35. 9. A bending machine comprising a bending member movably mounted, a post mounted on said member, a plunger located in said post and projecting beyond the end thereof, a clamp secured to the projecting end of said plunger to receive the end of a wire to be bent, a plate positioned to operate said plunger and the clamp thereon, and means to resist movement of said wire intermediate its ends.
40. 10. A bending machine comprising a bending member movably mounted, a post mounted on said member, a plunger located in said post and projecting beyond the end thereof, a clamp secured to the end of the plunger to engage the end of an article to be bent, an anti-friction member engaging the end of the plunger and upon which said plunger rides, a plate on to which said anti-friction member travels to operate said clamp, means for pressing the anti-friction member against the plate over which it travels, and means to resist movement of said article intermediate its ends. 70
45. 11. A bending machine comprising a bending member mounted for reciprocating movement in a curved path, a post mounted on said member to move it along said path, a plunger located in said post and projecting beyond the end thereof, a clamp secured to the end of the plunger, means for operating the plunger at each end of its path of travel, and means to resist movement of said article intermediate its ends. 80
50. 12. A bending machine comprising a bending member movable in a curved path, a post mounted on said member, a clamp mounted on the end of the post to receive the end of an article to be bent to move said end along said path, means for releasing said clamp and for retaining it in released position during movement of said post from bending position, and means to resist movement of said article intermediate its ends. 90
55. 13. A bending machine comprising a bending member movable in a curved path, a clamp mounted on said member to engage the end of an article to be bent to move said end along said path, means for releasing said clamp at the end of its travel to receive said article, means for closing said clamp in its reverse movement, means for opening the clamp at the end of its bending movement, and means to resist movement of said article intermediate its ends. 100
60. 14. A bending machine comprising a bending member movably mounted, a clamp mounted on said member to engage an article to be bent, means for opening said clamp at the end of its movement to receive said article, means for closing said clamp in its reverse movement, means for opening the clamp at the end of its bending movement, means for retaining said clamp in its open position during return movement of the clamp from its bending position, and means to resist movement of the article intermediate its ends. 110
65. 15. A bending machine comprising a bending member movably mounted, a clamp mounted upon said bending member to receive an article to be bent, a retaining plate 120

movably mounted to retain said clamp in a certain position, and means on said member to move said plate out of its path.

16. A bending machine comprising a bending member movably mounted, a clamp mounted upon said bending member to receive an article to be bent, a releasing plate to release said clamp, and a retaining plate movably mounted to engage said releasing plate.

17. A bending machine comprising a bending member movably mounted, a clamp mounted upon said bending member to receive an article to be bent, a releasing plate having a beveled surface to operate to release said clamp, a retaining plate movably mounted with a beveled surface to engage that on the releasing plate, and means on said member to engage said retaining plate to move it from the path of said member.

18. A bending machine comprising a movably mounted bending member having a clamp to engage an article to be bent, a releasing plate having a beveled surface and a flat surface, a movably mounted retaining plate having a flat surface located in the same plane as that on the releasing plate, and means on said member to engage the retaining plate to move it from the path of said member.

19. A bending machine comprising a movably mounted bending member having a clamp to engage an article to be bent, a releasing plate, a movably mounted retaining plate having a retaining surface located in the plane with the surface of the releasing plate, an easing cam located on said retaining plate, and means for moving the retaining plate from the path of movement of said member.

20. A bending machine comprising a feed device, a bending member movably mounted to receive an article to be bent, a second bending member movably mounted, and a detent comprising a part of the feed device and movably mounted to engage a pile of said articles, said detent being located in the path of movement of said second bending member for operation thereby to release one of said articles at each bending operation.

21. A bending machine comprising bending mechanism and a feed device comprising a chute for articles to be bent, a detent to successively engage said articles and to release them to present them in bending position, said detent having a beveled end to raise and lower the pile of articles in said

chute in each reciprocating movement of the detent, and means for operating the detent.

22. A bending machine comprising bending mechanism and including a feed device comprising a chute for articles to be bent and a detent to successively engage said articles, and a reciprocating member around which said articles are bent, said reciprocating member engaging said detent in each of its reciprocating movements to operate the

23. A bending machine including a feed device comprising a pair of chutes, bending mechanism to bend an article received from said chutes, a post reciprocatingly mounted to resist movement at its center of an article being bent, detents, a connection between said detents, and a finger projecting from said connection into the path of movement of said post.

24. A bending machine comprising a supporting bending member positioned to receive an article to be bent intermediate the ends of said article, active bending members spaced from said supporting member and movable in a curved path thereabout, means for operating said active members, and means on said active members spaced from said support to grasp the ends of said article and move them with a sweeping action toward each other.

25. A bending machine comprising a supporting member to receive an article to be bent intermediate the ends of said article, a pair of shafts, means for applying force directly to said shafts to rotate them, bending arms secured to and projecting radially from said shafts, and means on the ends of said arms to grasp the ends of said article and exert a yielding hold thereon as they are swept in a curved path toward each other and about said supporting member by said arms.

26. A bending machine comprising a supporting member to receive an article to be bent intermediate the ends of said article, active bending members spaced from said supporting member and movable in a curved path thereabout, means for operating said active members, means for simultaneously moving said supporting member in opposition to said active members, and means on said active members and spaced from said supporting member to receive the ends of said article and move them with a sweeping action toward each other.

ANTON VAN VEEN.
